SWITCHING APPARATUS WITH PERIODICALLY OPERATED CONTACTS

Carl Zellweger, Zurich, and Hans Hugo Durheim, Berne, Switzerland, assignors to International Standard Electric Corporation, New York, N. Y., a corporation of Delaware

Application May 8, 1942, Serial No. 442,273
In Switzerland June 6, 1941

10 Claims. (Cl. 200—28)

1

This invention relates to a switching apparatus with periodically actuated contacts such as used for example in contacting converters for converting alternating current into direct current or direct current into alternating current.

A particular object of the present invention is to provide an improved switching apparatus employing an advantageous type of rolling and pressure engagement of the contact members and improved controlling or actuating means for a rolling type of movable contact designed to operate with a maximum or accelerated speed during the change-over interval as is desired to effect a sparkless change-over switching engagement and to adapt the change-over period as much as possible to the short time interval during which the current passes through zero. A further object is to produce an actuating means which in its operation will substantially eliminate the objectionable vibrations common to many types of converter switching mechanisms as at present employed.

The switching apparatus according to the present invention is characterised by at least one rolling contact which is periodically moved to and fro.

The invention will now be described in connection with some embodiments which are schematically represented in the accompanying drawing. In this drawing only such parts are shown which are necessary for the understanding of the invention, and similar parts are designated by equal reference numerals.

In the drawing

Fig. 1 shows partly in section a side view of a first embodiment for use in a triphase contacting converter.

Fig. 2 is a front view of an arrangement of the stationary contact members providing stationary feeding to the movable contact member of a phase, the said arrangement being used in the contact devices of the switching apparatus according to Fig. 1.

Fig. 3 shows a second embodiment in which the driving mechanisms for the contact devices do not comprise springs, and

Figs. 4 and 5 are views in front and side elevation showing a modified driving mechanism for operating one phase of a third embodiment of the invention.

The switching apparatus of Fig. 1 comprises one contact device for each phase of the triphase current, said contact device having two stationary contact members 1 and 2 and a stationary feeder contact member 3 as shown in Fig. 2. The con-

2

tact members 1, 2 and 3 are mounted on a plate 5 of insulating material, the spaces between said contact members being at least partly filled with insulating material up to the height of the contact faces to provide an almost uninterrupted rolling surface for the rolling contact. The contact members are provided with connecting terminals (not shown) for the connecting lead. The plate 5 and the contact members 1, 2 and 3 may be designed in such a way that they can be easily replaced. The plate 5 and the contact members 1 and 2 may be provided with corresponding means for changing the relative position of the contacts with respect to one another and the co-operating rolling contact, i. e. the movable contact member 4, whereby the contact device may be adjusted with respect to the zero point of the current of this phase and the change-over time.

20 The plate 5 is mounted on a contact support 6, preferably of high quality light metal and sliding in slide grooves of the fixed part 7. A pressure spring 8 resting on one side on the adjusting plate 9 presses against the contact support 6. The pressure spring 8, the stress upon which remains constant after the adjustment of the pressure, serves to provide the desired contact pressure between the contacts 1, 2 and 3 on the one hand and the rolling contact 4 on the other hand by pressing the contacts mounted on the contact support 6 against the rolling contact 4. This spring may be tensioned more or less by means of the adjusting screw 11 screwed into the fixed part 10, whereby the contact pressure is changed. The screw 11 is secured by means of the nut 12. The parts 7 and 10 may form part of the casing of the switching apparatus; part 10 may belong to a cover which may be fixed to the part 7 of the casing by means of screws or latches. With such a construction the stationary contact members of the contact device may be easily adjusted or removed, for instance, for maintenance purposes.

25 The movable contact member 4 is mounted on an insulating piece 14 and is of a form and of dimensions whereby its peripheral contact surface has an engaging area coextensive with and conforming to the surfaces of the stationary members 1, 2, 3, and 5 engaged thereby. This 30 insulating piece in turn is mounted on a flange 13 of the sector-shaped control member 15. The latter is pivoted on the pivot 16 of the slide 17, said pivot supporting also an idler wheel 18 pressed against the cam disc 20 of this phase by 35 means of pressure spring 19. The slide 17 is

slideably mounted on two guiding rods 21 screwed into the fixed part 22, which may form part of the casing of the switching apparatus, and secured by nuts 23. The three cam discs 20, 20' and 22" of the three phases are mounted on the common driving shaft 24 driven by a synchronous motor (not shown) and are shifted from one another by 120°.

The switching apparatus according to Fig. 1 operates as follows:

Upon rotation of the cam disc 20 in the direction of the arrow to the position shown in dotted lines, the idler 18, due to the action of spring 19 pressing on the slide 17, follows the cam disc, so that the rolling contact 4 rolls over contact 2, the insulating portion between the contacts 1 and 2 and the feeder 3 until the control member 15 finally reaches the position indicated by dotted lines. It will be evident, that, since the control member forms part of a rolling wheel, so that the distance between the contacting point and the plane determined by the axis of the driving shaft and the idler does not change, the contact pressure determined by the pressure spring 8 will be the same in all positions of the control member, so that chattering cannot occur. Upon further rotation of the cam disc 20 the control member 15 starts to return, the cam disc pressing the idler 18 downwards against the pressure of spring 19.

It will be evident, that the speed increases from zero at the beginning of the movement of the control member in one direction and from zero at the beginning of the movement in the other direction to a maximum value at about midway, so that the speed of the rolling contact is greatest when it passes from contact 2 to contact 1 or from contact 1 to contact 2, i. e. during the change-over period. Thereby the change-over time is substantially reduced as compared with switching apparatus with continuously rolling contacts and the change-over is improved. The cam discs do not need to be circular but may be adapted to the requirements of the desired change-over speed.

The switching apparatus according to Fig. 3 comprises for each phase two co-operating cam discs 25 and 26 of equal size, which are mounted on the shafts 27 and 28 respectively and which always have the same angular position. Each cam disc is provided at its periphery with a ball race 29, 30. Between the ball races 29, 30 is arranged an idler 18 pivoted on the pivot 31 of the control member 15 the axis of the shafts 27 and 28 and the idler 18 being in the same plan. The cam discs with the ball races and the idler are so dimensioned and the shafts 27, 28 are so spaced, that the ball races 29, 30 and the idler 18 are permanently in touch with one another. The idler 18 may also be provided with a ball bearing or the like and is pressed against the guide rail 32 by means of the contact pressure spring 8 (shown in Fig. 1) which exerts pressure upon the stationary contact members via the control member 15. The guide rail 32 may form part of the casing or may be mounted thereon and may be provided with a groove in which the idler is rolling, so that a displacement in the direction of the axis of the driving shafts 27, 28 is prevented. The contact device may be exactly similar to that shown in Fig. 1.

The two shafts 27, 28 are driven by a motor (not shown) on the shaft of which a toothed wheel 33 is mounted which is in engagement with two toothed wheels 34, 35 of equal size mounted on

the shafts 27, 28. Thus said shafts rotate in the same sense and with the same speed. Of course another ratio could be used, if desired, between the toothed wheel 33 on the one hand and the toothed wheels 34, 35 on the other hand. The cam discs of the driving mechanisms for the other two contact devices of the contacting converter are mounted on the same shafts 27, 28 and are displaced from one another and against the shown cam discs by 120°. These driving mechanisms are exactly similar to that shown.

The switching device of Fig. 3 operates as follows:

If the two gear wheels 34, 35 are rotated clockwise by the synchronous motor the ball race 30 of cam disc 26 pushes the idler 18 upwards whilst the cam disc 25 retracts. Thereby the movable contact member mounted on the control member is rolled on the stationary contact members until the two cam discs have reached their uppermost position which is shown in dotted lines, whereupon the idler 18 is again pushed downwards by the cam disc 25, whilst the cam disc 26 retracts.

The switching apparatus of Figs. 4 and 5 comprises as a driving mechanism for each phase but one single cam disc 37 which is mounted on the common driving shaft 41 together with the not shown cam discs for the other phases. The cam disc 37 which is recessed at its periphery is provided with a ball race 38 which together with the recessed portion of the disc form a guiding groove 39 as it is evident from Fig. 4. In the guiding groove rolls a guide roller 40 pivoted on the pivot 14 of the control member 15, the other end of the pivot supporting an idler 18 which rolls on the guide rail 32. The latter may also be provided with a groove to prevent lateral displacement and may form part of the casing or may be fixed thereto. The three cam discs are shifted against one another by 120°.

The contact device which is not shown may be similar to that of Fig. 1.

As it will be evident from the Figs. 3, 4 and 5 the driving mechanisms of the two switching apparatus shown in these figures do not possess restoring springs nor sliding parts but only rolling parts so that the driving power required will be small. Due to the lack of restoring springs and of sliding parts the stress and consequently wear of the elements will be small, and vibration reduced and in consequence greater reliability in operation is obtained.

What is claimed is:

1. Switching apparatus of the character described comprising a stationary multiple contact member and a movable contact member provided with a curved contact adapted for rolling engagement with the stationary contact member, actuating means for the movable contact member with constant engagement with one of the contacts thereof adapted to impart a to and fro rolling movement thereto, said actuating means including a rotary shaft, an eccentric thereon and said shaft being positioned substantially in alignment with the axis of rotation of the movable contact member.

2. Switching apparatus of the character described comprising a stationary multiple contact member and a movable contact member adapted for rolling contact engagement with the stationary contact member with constant engagement with one of the contacts thereof, said movable member being provided with a pivotal connection supported for reciprocal movement in a substantially rectilinear path, an operating shaft

positioned substantially in alignment with said path and an eccentric carried by the shaft arranged to effect movement of the pivotal connection thereby to have accelerated motion at the intermediate portion of each stroke thereof.

3. Switching apparatus of the character described comprising a stationary contact member having two longitudinally separated and insulated contacts and a third elongated insulated contact coextensive with the first contacts, a movable contact member provided with a curved surface contact and having rolling contact engagement with the stationary contacts and means to impart a to and fro rolling movement to the movable contact member in a direction parallel to the elongated contact.

4. Switching apparatus of the character described comprising a stationary contact member, a movable contact member provided with a curved surface contact for rolling contact engagement with the stationary contact, a controlling member pivotally connected to the movable contact member at the axis of rotation thereof and actuating means for reciprocating the control member to effect rolling movement of the movable contact member.

5. Switching apparatus of the character described comprising a stationary contact member, a movable contact member provided with a curved surface contact for rolling contact engagement with the stationary contact, a controlling member pivotally connected to the movable contact member at the axis of rotation thereof and actuating means for reciprocating the control member to effect rolling movement of the movable contact member, and one of said contact members being resiliently supported to effect pressure engagement between the contact surfaces.

6. Switching apparatus of the character described comprising a stationary contact member, a movable contact member provided with a curved surface contact for rolling contact engagement with the stationary contact, a controlling member supported for movement in a plane coinciding with the axis of rotation of the movable contact member and pivotally connected thereto, a rotary eccentric cam for actuating the controlling member and said cam having its axis of rotation in alignment with the path of movement of the axis of the movable contact member whereby accelerated speed of the rolling movement occurs at the intermediate period thereof.

7. Switching apparatus of the character described comprising a stationary contact member, a movable contact member provided with a curved surface contact for rolling contact engagement with the stationary contact, a controlling member supported for movement in a plane coinciding with the axis of rotation of the movable contact member and pivotally connected thereto, a roller journaled on the pivotal con-

nexion, a rotary eccentric cam for actuating the controlling member, said cam having its axis of rotation in alignment with the path of movement of the axis of rotation of the movable contact member and a spring supported for engagement with the controlling member at the side opposite to the roller engagement with the cam.

8. Switching apparatus comprising a movable contact means periodically rolled to and fro, a stationary contact member periodically touched by said movable contact member, actuating means for the movable contact member consisting of two synchronously rotated cam discs having equal angular positions, a control member pivotally connected to the movable contact member and having an idler engaged by the cam discs, said cam discs having the axis of rotation positioned in alignment with the path of movement of the roller and a guide rail engaged by the roller and extending in a plane parallel to a straight line passing through the centers of rotation of the cam discs.

9. Switching apparatus of the character described comprising a stationary contact member, a movable contact member provided with a curved surface contact for rolling contact engagement with the stationary contact, a roller pivotally supported on the movable contact member at its axis of rotation and actuating means therefor comprising a rotatable eccentric provided with a groove receiving the roller and said eccentric having its axis of rotation in alignment with the path of movement of the movable contact member axis thereby to effect accelerated speed at the intermediate period of the contact member movement.

10. Switching apparatus of the character described comprising a stationary contact member, a movable contact member adapted for rolling contact engagement with the stationary contact and actuating means therefor consisting of two rollers pivoted to the movable contact member at its axis of rotation, an eccentric cam provided with a cam groove receiving one of the rollers, said cam having its axis of rotation in alignment with the path of movement of the rollers and a guide rail positioned parallel to said path and engaging the other of said rollers.
